UNITED STATES PATENT OFFICE.

CHARLES FORTH, OF OTTAWA, ONTARIO, CANADA, ASSIGNOR TO THE FLEXIBLE METAL HOSE COMPANY, LIMITED, OF OTTAWA, ONTARIO, CANADA.

SELF-LOCKING ATTACHMENT FOR RAILWAY-SWITCH HANDLES.

1,353,825.

Specification of Letters Patent. Patented Sept. 28, 1920.

Application filed March 6, 1917. Serial No. 152,750.

To all whom it may concern:

Be it known that I, CHARLES FORTH, a citizen of the United States of America, and a resident of 26 Wellington street, in 5 the city of Ottawa, in the Province of Ontario, Dominion of Canada, have invented certain new and useful Improvements in Self-Locking Attachments for Railway-Switch Handles, of which the following is 10 a full description.

This invention relates to improvements in self locking attachment for railway switch handles, and the objects of the invention are to provide a simple and effective form of attachment which may be applied to railway switch handles, by means of which the handle may be locked in closed position. A further object is to construct this device of few and simple parts, each one being adapted to perform the functions required of it. 15

The invention consists essentially of the improved construction hereinafter described in detail in the accompanying specification and drawings.

20 In the drawings,

Figure 1 is a side view, partially in section, of an embodiment of the invention.

Fig. 2 is a plan view of the same.

Fig. 3 is a section on the line 2—2 of 25 Fig. 1.

Referring to the drawings, A represents a switch handle of any well known type being formed with bifurcated ends 10 and 11 connected by a cross bar 12. B represents 30 the tongue of the switch stand, having the usual aperture 13 therein. C represents the casing forming part of my improved attachment adapted to fit over the handle A and being provided with clamping means, by 35 which it may be clamped in position thereon. The clamping means I have shown, include tongues 14 and 15 adapted to extend on opposite sides of the cross bar 12. A set screw 16 extends through the tongue 14, 40 and a clamping bolt 17 extends from an extension 18 on the casing, the head of which bolt is adapted to bear against the handle as 45 shown.

Within the casing is pivotally mounted a bolt spindle 19 having an operating handle 20 at the top thereof. This spindle is formed with a squared portion 21 on which the locking bolt D is mounted. This locking bolt includes an arm 23 having a projection 24 designed to enter the aperture 13 in the tongue B. The bolts normally enter into position by means of a compression spring 25 bearing at one end against the end of the casing and at the other end against the projection 26 on the locking bolt. The projection 24 is formed with suitable beveled edges whereby it will slip into engaged position after the manner of a latch. 55

As many changes could be made in the above description and many apparently widely different embodiments of my invention within the scope of the claim constructed without departing from the spirit or scope thereof, it is intended that all matter contained in the accompanying specification and drawings shall be interpreted as 60 illustrative and not in a limited sense. 70

What I claim as my invention is:

In a device of the class described, the combination with a switch handle and the tongue of a switch stand, of a casing secured to the switch handle and covering the end of the tongue, a bolt spindle pivotally mounted vertically within the casing and 75 having an offset operating handle, said spindle having a squared portion, a laterally movable bolt engaging with the squared portion, of the spindle and operated thereby, and having an offset projection provided 80 with beveled edges to facilitate automatic engagement with the said tongue, a projection on the bolt and spring means between the projection and the end of the casing for retaining the bolt normally in 85 locked position. 90

In witness whereof I have hereunto set my hand in the presence of a witness.

CHARLES FORTH.

Witness:

RUSSEL B. BRAIT.
